UNITED STATES PATENT OFFICE.

WILLIAM H. GRAY, OF BROOKLYN, NEW YORK, ASSIGNOR TO THE GLEN COVE MACHINE COMPANY, (LIMITED,) OF SAME PLACE.

PRESSER-BAR FOR WOOD PLANING OR MOLDING MACHINES.

SPECIFICATION forming part of Letters Patent No. 361,506, dated April 19, 1887.

Application filed February 11, 1887. Serial No. 227,262. (No model.)

To all whom it may concern:

Be it known that I, WILLIAM H. GRAY, of Brooklyn, (Green Point,) in the county of Kings and State of New York, have invented a new and useful Improvement in Presser-Bars for Wood Planing or Molding Machines, of which the following is a specification.

In wood-planing machines, and more particularly in molding-machines, there is commonly arranged above the lower cutter-head a cross-bar which extends from side to side of the machine and which has attached to it a presser or adjustable presser-foot. This bar has been commonly hinged at one side of the machine, and at the opposite side thereof has been inserted in a loop or shackle or otherwise held in place, so as to provide for its adjustment upward and downward.

In carrying out my invention I hinge the above-described cross-bar at one end, as has been before done; but I provide a novel means of securing the bar at its free end, which enables the bar to be adjusted accurately upward and downward, and which also provides for expeditiously freeing the end of the bar from the means which hold it, in order to swing the bar upward away from the cutter-head; and the invention which relates to such means for holding and adjusting the free end of the bar consists in novel combinations of parts and features of construction, hereinafter described, and pointed out in the claims.

In the accompanying drawings, Figure 1 is an elevation in a plane transverse to the length of the machine, showing the parts which are necessary to illustrate my invention, the cutter-head and the side frames and bearings being shown in dotted outline. Fig. 2 is a plan of the parts shown in Fig. 1 by full lines. Fig. 3 is an end view of the parts shown in Fig. 1, looking from the right hand of said figure; and Fig. 4 is a horizontal section upon about the plane indicated by the dotted line xx , Fig. 3.

Similar letters of reference designate corresponding parts in all the figures.

A designates the lower cutter-head, A' the cutter-head boxes, and A² portions of the side frames of the machine, all of which parts are shown in Fig. 1 by dotted lines, as they do not directly concern my invention.

B is a cross-bar, which is usually arranged above the lower cutter-head and transversely of the machine in a wood-planing machine, and upon this bar is a presser, which, as here shown, consists of a stock-piece, C, secured to the bar B, and an adjustable foot piece or presser, C', which may, by means of a screw, c, be adjusted upward and downward relatively to the stock-piece C and the supporting-bar B. The bar B is usually hinged at one side of the machine, and its free end is connected with means at the opposite side of the machine whereby the bar may be adjusted upward and downward and held securely in position after such adjustment. At one end of the bar I have represented a bracket, D, which may be bolted to one of the side frames of the machine, and to which the upright link or post E is hinged or pivoted at e, and at the other or free end of the bar is a bracket, D', from which rises a round post or column, E'. The end of the bar B may be pivoted or hinged at e' to the upright link or connection E, and the slot e² in the link or connection E provides for adjusting that end of the bar upward and downward to suit considerable variations in height.

The means for securing the free end of the bar in place, and for adjusting it upward and downward, consist of a head, F, upon the post or column E', a collar or slide, F', which is fitted to both slide and turn upon the post E', and a screw, F², which has its bearing f in the head F and which is threaded to engage a nut formed in the collar F'. The collar F' has on one side a flattened surface, f', on which the free end of the bar B is secured by means of a clamping-screw, f², and the free end of the bar may have in it a slot, b, as shown by dotted lines in Fig. 1, through which the clamping-screw f² passes. When the clamping-screw f² is tightened, the end of the bar B is held securely against the flattened surface f' of the collar F'; but it will be observed that the slot b provides for turning the collar upon the post E' whenever the clamping-screw f² is loosened, in order to remove the clamping-screw entirely from the bar B and permits said bar to be swung upward. The adjustment of the bar upward and downward is provided for by turning the screw F². After the free end of the bar

is secured by the clamping-screw f^2 , any upward or downward adjustment of the bar is secured by turning the screw F^2 , and the bar between its periods of adjustment is held with 5 sufficient firmness and rigidity to enable the presser C' to properly perform its work.

The head F and the collar F' are both fitted to turn freely on the post E' , and whenever the bar B is freed from the clamping-screw f^2 , or 10 whenever said screw is slightly released, the head F , the collar F' , and the screw F^2 may be turned on the post E' as one piece, to disengage and leave free the end of the bar B .

What I claim as my invention, and desire to 15 secure by Letters Patent, is—

1. The combination, with the lower cutter-head and side frames of a planing or molding machine, of a bar carrying a presser extending across the machine and hinged at one end 20 on one side of the machine, a post at the other

side of the machine, a slide movable vertically on the post and to which the end of the bar may be secured, and a screw, substantially parallel with the post, by which the slide may be raised and lowered, substantially as herein described. 25

2. The combination, with the bar B , hinged at one end and carrying a presser and slotted at the other end, of the post E' , the head F , and the collar F' , both fitted to turn on the 30 post and the collar being provided with a flat face, f' , and a clamping-screw, f^2 , for securing the bar, and the adjusting-screw F^2 , connecting the said head and collar and serving to adjust the collar vertically on the post, substantially 35 as herein described.

WM. H. GRAY.
